COUNTERWEIGHT MECHANISM FOR OIL
WELL PUMPS

John C. Slonmeger, Milwaukee, Wis.

Application May 4, 1934, Serial No. 723,847

4 Claims. (Cl. 74—590)

This invention relates to oil well pumps of the reciprocating type and more particularly to counterweight mechanism therefor.

Oil well pumps of the reciprocating type are ordinarily actuated by a crank operated walking beam counterweighted to counteract the load imposed by the long string of pump rods which extend to the pump at the bottom of the well.

As heretofore arranged, such systems set up objectionable periodic forces which react upon the driving mechanism and the pump rods to produce objectionable noise, premature wear, and rod breakage. I attribute this objectionable condition to the fact that the counterweight is ordinarily connected to the walking beam to reciprocate in unison therewith, so that the counterweight thus constitutes in effect an integral part of the reciprocating pump-driving system, and its mass, thus combined with that of the system, increases to an objectionable degree those inertia forces which result from the reciprocating motion.

This objectionable condition is aggravated by the resiliency of the reciprocating pump-driving system, and particularly the pump rods, and by inevitable slackness between the rotating driving crank and the reciprocating system as heretofore arranged.

An object of the present invention is to provide a counterweight for systems of this type so arranged as to avoid the objectionable reactions heretofore experienced. This I have accomplished by connecting the counterweight to the rotating crank in a manner to impart to the counterweight a reciprocating motion independently of and preferably different from that of the reciprocating pump-driving system, so that the counterweight does not constitute a part of the latter.

A more specific object is to so arrange the parts that the opposed forces resulting from the counterweight and pump rod loads are utilized to maintain all connections taut throughout each reciprocating cycle.

Other objects and advantages will appear, expressed or implied, from the following description of an illustrative embodiment of this invention.

The single figure of the accompanying drawing shows a reciprocating pump rig equipped with a counterweight arranged in accordance with the present invention.

The pump operating mechanism shown includes a conventional walking beam 10 rockably supported intermediate its ends upon the usual

Sampson post 11. The usual string of pump rods is supported and actuated in a well known manner from that end of the beam not shown, and the other end 12 of the beam is actuated through a conventional link 13 from the pin 14 of a rotating crank 15. The beam 10, link 13, and pump rods (not shown), constitute conventional parts of the usual reciprocating pump-driving system and need no further description.

The rotating crank 15 is also a conventional part of a standard pump rig and in this instance is shown supported and actuated by a speed reducer unit 16 driven from any appropriate power source.

In this instance a counterweight 17 is provided, arranged to counteract the weight of the pump rods but in such manner as to avoid the objectionable periodic reactions heretofore experienced.

I have discovered several ways by which this can be accomplished, but the arrangement shown has proven entirely satisfactory. The counterweight is supported by the crank 15 independently of the reciprocating pump-driving system. It is shown connected to the crank through a link 20 suspended from the crank pin 14. In this instance the link 20 is connected to a lever 18 to which the counterweight is attached and by which the latter is guided during reciprocation imparted to it by the crank. The lever 18 is shown fulcrumed upon a horizontally offset pivot pin 19.

It will be noted that with the parts thus arranged, the motion of the counterweight 17 is different in kind from that of the walking beam 10; that is to say, the rate of acceleration and deceleration of the counterweight is different from that of the walking beam at corresponding points in their operating cycles. For instance, the walking beam attains a maximum velocity during travel of the crank pin 14 through a point in an upper quadrant of its circular path P, whereas the counterweight attains a maximum velocity during travel of the crank pin through a point in a lower quadrant of that path, and as the crank 15 passes downwardly through the horizontal position shown, the counterweight is accelerating while the walking beam is decelerating.

The counterweight thus forms a part of a reciprocating system having a reciprocating motion different in kind from that of the pump actuating system, and yet the weight of the counterweight system always reacts in a manner to counteract the pump rod load.

It will be noted that the counterweight is connected to the pump reciprocating system through the rotating driver, both links 20 and 13 being independently connected to the pin 14 constituting a part of the rotating crank. The link 20, under the counterweight load, always pulls downwardly upon the pin 14 throughout crank rotation, while the link 13, under the pump rod load, always pulls upwardly on the pin. With such an arrangement no slack can ever develop between the crank and the driven links.

Various changes may be made in the embodiment of the invention hereinabove specifically described without departing from or sacrificing the advantages of the invention as defined in the appended claims.

I claim:—

1. In an oil well pumping mechanism the combination of a rotary driver, a reciprocating pump rod actuator including a walking beam, a reciprocating counterweight, motion transmitting means connecting said rotary driver with said actuator, and separate motion transmitting means directly connecting said rotary driver with said counterweight and through which said

counterweight reacts on said driver to oppose the pump rod load.

2. In an oil well pumping mechanism the combination of a rotary driver, a reciprocating walking beam, a reciprocating counterweight, reciprocating means directly connected with said rotary driver for reciprocating said walking beam, and separate reciprocating means directly connected with said rotary driver for reciprocating said counterweight.

3. In an oil well pumping mechanism the combination of a rotary driver, a reciprocating pump rod actuator including a walking beam, a reciprocating counterweight, a link directly connected with said rotary driver for reciprocating said walking beam, and a separate link directly connected with said rotary driver for reciprocating said counterweight.

4. In an oil well pumping mechanism the combination of a rotary driver, a reciprocating pump rod actuator including a walking beam, a counterweight lever, a link directly connected with said rotary driver for actuating said actuator, and a separate link directly connected with said rotary driver for reciprocating said lever.

JOHN C. SLONNEGER.
